UNITED STATES PATENT OFFICE.

EDWARD B. ALLEN, OF NEWTOWN, CONNECTICUT, ASSIGNOR TO THE SINGER MANUFACTURING COMPANY, OF ELIZABETH, NEW JERSEY, A CORPORATION OF NEW JERSEY.

CLAMP-SPREADING MECHANISM FOR BUTTONHOLE-SEWING MACHINES.

Application filed April 11, 1924. Serial No. 705,817.

To all whom it may concern:

Be it known that I, EDWARD B. ALLEN, a citizen of the United States, residing at Newtown, in the county of Fairfield and State of Connecticut, have invented certain new and useful Improvements in Clamp-Spreading Mechanisms for Buttonhole-Sewing Machines, of which the following is a specification, reference being had therein to the accompanying drawings.

The present invention has for an object to provide a buttonhole sewing machine with an automatic clamp-spreading mechanism designed to impart simultaneous and equal spreading movements to the clamp-sections and having a single manually operable element and connections for regulating the extent of the equal spreading movements imparted to the work-clamp sections.

A further object of the invention is to provide for the desired regulation while maintaining constant the respective spread positions of the work-clamp sections, so that the area of material exposed between the upper clamping feet to the action of the sewing mechanism will remain constant regardless of the amount of spreading movement imparted to the clamp-sections.

To the attainment of the ends in view, use has preferably been made of the clamp-spreading toggle mechanism disclosed, for example, in my Patent No. 1,372,472, re-issued April 4, 1922, under No. 15,324. One of the lateral clamp-engaging slide-blocks of said toggle mechanism is, for the purpose of the present disclosure, extended at its outer end and fitted with a pivoted cam-disk having an eccentric operative edge and a regulating handle which may be readily grasped by the operator. The supporting plate for the toggle mechanism has secured thereto a stop-element so positioned as to be encountered by the operative edge of the cam-disk and thus, through the toggle mechanism, limit or determine the unspread positions of both clamp-sections.

By shifting a single regulating handle, the operator may, at will, vary the amount of spread of the work-clamp sections while maintaining constant the respective spread positions of said sections and insuring at all times that the work will be subjected

to equal spreading actions at the opposite sides of the longitudinal center line through the buttonhole-slit, an important consideration particularly in machines which cut the buttonhole before sewing it.

In the accompanying drawings, Fig. 1 is a horizontal section through the bracket-arm standard of a sewing machine embodying the invention, showing the work-clamp in plan. Fig. 2 is a bottom plan view of a fragment of the clamp-spreading-toggle supporting plate of the work-clamp mechanism. Fig. 3 is a section through the clamp-spreading-toggle supporting plate transversely of the machine bed and Fig. 4 is a plan view of the left lateral slide-block showing its end extension.

The machine comprises the usual frame including the bed 1 upon which is mounted the usual longitudinal slide-frame 2 carrying the cross slide plate 3 to which is pivotally connected at 4, 4 the separable work-clamp sections 5, 5 including the usual work-supporting plates 6, 6 and upper clamping feet 7, 7. The clamp sections 5, 5 are normally urged to their respective unspread positions by means of the usual springs 8, 8.

The clamp-spreading mechanism is in the form of a toggle designed to impart equal spreading movements to the respective clamp-sections. It comprises the lateral slide-blocks 9, 9 carrying the abutment screws 10, 10 against which rest the heads of the screws 11, 11 mounted on the respective clamp-sections 5.

The slide blocks 9 are connected, respectively, to the opposite ends of the lever 12 by means of the links 13, 14, the latter having an extension 15 adapted to be struck by forward movement of the clamp-unspreading arm shown in section at 16. The pivotal connection or pin 17 between the lever 12 and link 13 is embraced by the forked inner end of the toggle straightening lever 18 the outer end of which is given a forward push by the element 19 mounted on a third or downwardly extending arm of the clamp-closing lever 20. Except as hereinafter described the constructive features of the present device are fully disclosed in my said reissued patent; the clamp-closing lever 20 being actuated as usual from the continuously rotating power means or pulley 20'.

The left-hand lateral slide-block 9 is formed with an upwardly offset end extension 21 terminating in a circular head 22 to the under face of which is pivoted at 23 the regulating stop 24 in the form of a cam-disk having an active eccentric edge-operation, between the points 25, 26, Fig. 2, which strikes the outer end of the stop-arm 27 adjustably fixed to the toggle supporting plate by the screw and slot connections 28. The cam-disk 24 is formed with a regulating handle 29 which is readily accessible to the operator. The disk 24 also carries a pin 30 located in the recessed quadrant 31 of the head 22; the latter bearing indicating marks in connection with which the pin 30 serves as a pointer to indicate the amount of spreading movement imparted to the clamp-sections. The cam-disk 24 strikes the stop 27 when the toggle 12, 13, 14 is broken and limits or determines the unspread positions of the respective clamp-sections. A shift of the regulator 29 affects both clamp-sections equally so that the spreading or unspreading actions are always equal at the opposite sides of the longitudinal center line of the buttonhole. Moreover, the spread positions of the clamp-sections are not affected by a shift of the regulator 29 and the area of work exposed to the sewing mechanism is always the same, thus affording a desired uniformity of sewing relations between the sewing mechanism and the work-clamp, regardless of the amount of spread imparted to the clamp-sections.

Having thus set forth the nature of the invention, what I claim herein is:—

1. In a buttonhole sewing machine, the combination with the machine bed, of a work-clamp having separable sections, continuously rotating power means, automatic clamp-spreading mechanism actuated by said power means and including means interconnecting the clamp-sections for simultaneously spreading the latter, spring means for returning said sections to their unspread positions, and a manually adjustable regulator in the form of a stop disposed at the side of the machine bed and cooperatively related to said interconnecting means to limit the return movement of said sections under the influence of said spring means.

2. In a buttonhole sewing machine, the combination with the machine bed, of a

work-clamp having separable sections, continuously rotating power means, automatic clamp-spreading mechanism actuated by said power means and including means interconnecting the clamp-sections for simultaneously spreading the latter, spring means for returning said sections to their unspread positions, and a manually adjustable regulating lever disposed at the side of the machine bed and having an eccentric stopportion cooperatively related to said interconnecting means to limit the return movement of said sections under the influence of said spring means.

3. In a buttonhole sewing machine, a work-clamp having separable sections, means including a toggle mechanism for simultaneously spreading said sections, and a manually operable regulating stop for varying the limit to which the toggle mechanism may be moved to unspread the clamp-sections.

4. In a buttonhole sewing machine, a work-clamp having separable sections, a slide-block support, laterally separable slide-blocks carried by said support and engaged by said sections, a toggle-mechanism for shifting said slide-blocks simultaneously in opposite directions, a stop-element carried by one of said slide-blocks, and a coacting stop-element carried by said slide-block support, one of said stop-elements being manually operable to regulate the range of action of the toggle mechanism.

5. In a buttonhole sewing machine, a work-clamp having separable sections, laterally separable slide-blocks engaged by said sections, one of said slide-blocks having an end-extension, a toggle mechanism for shifting said slide-blocks simultaneously in opposite directions, a manually operable stop-cam mounted on said end-extension, and a stop engaged by said cam to limit the simultaneous inward motions of the slide-blocks.

6. In a buttonhole sewing machine, a work-clamp having separable sections, a toggle mechanism for spreading said sections, and a single manually operated stop for regulating the amount of spreading movement imparted to said sections by said toggle-mechanism.

In testimony whereof, I have signed my name to this specification.

EDWARD B. ALLEN.
